UNITED STATES PATENT OFFICE.

ARTHUR J. BAZELEY, OF CLEVELAND, OHIO, ASSIGNOR TO THE NATIONAL MALLEABLE CASTINGS COMPANY, OF CLEVELAND, OHIO.

CAR-COUPING.

1,144,316.

Specification of Letters Patent. Patented June 22, 1915.

Application filed December 16, 1912, Serial No. 736,889. Renewed May 20, 1915. Serial No. 29,433.

To all whom it may concern:

Be it known that I, ARTHUR J. BAZELEY, a citizen of the United States, residing at Cleveland, Cuyahoga county, Ohio, have invented new and useful Improvements in Car-Couplers, of which the following is a specification, reference being had to the accompanying drawings, in which—

Figure 1 is a sectional plan of my improved coupler showing the parts in locked position; Fig. 2 is a section on lines II—II of Fig. 1; Fig. 3 is a sectional plan, and Fig. 4 is a sectional side view, showing the parts in lockset position; Fig. 5 is a sectional plan, and Fig. 6 is a sectional side view, showing the parts in knuckle-thrown position, and Fig. 7 is a section on lines VII—VII of Fig. 1.

My invention relates to car couplers and is designed to provide a coupler in which the major portion of the pulling strains is carried back through the knuckle-tail and is thence transmitted to the coupler head, and in which the knuckle pin is relieved of strain, thus enabling the hub of the knuckle and the ears of the coupler head to be made of heavier section through the utilization of a smaller pivot pin.

To this end I provide a knuckle which is so constructed and supported by the coupler head, that under the heavy pulling strains of service, in spite of the tendency of the knuckle to move and stretch, the maintenance of the proper gage between the guard arm and the nose of the knuckle will be insured.

My invention also relates to the various parts which I have particularly described and claimed herein.

Referring to the drawings, A indicates the coupler head, B the knuckle, C the lock, D the opener, and E the lifter. The knuckle B is pivoted to the head A by the knuckle pin 2 and the knuckle pin holes in the ears 3 are so enlarged that in the operation of the coupler the pin is entirely relieved of strain under all normal draft and buffing stresses.

Upon the upper surface of the knuckle-tail and at its rear side is located a pulling lug or hook 4, the forward surface of which is preferably concave and which coacts with a convexly shaped shoulder 5 upon the roof of the coupler cavity.

To prevent the knuckle tail from bending

downwardly when it is under pulling 55 stresses transmitted through the hook 4 to the coupler head, and from disengaging from the shoulder 5, I provide a shelf 6 on the floor of the coupler head. The shelf 6 immediately underlies the rear end of the 60 knuckle tail when in locked position, thus giving enough clearance for the normal movements of the knuckle, and providing an effective support against vertical distortion 65 of the tail and the consequent disengagement of the pulling hook 4 and the shoulder 5.

Upon the upper and lower surfaces of the knuckle tail, just to the rear of the hub, 7, are formed inclined projections 8, 8', 70 somewhat V-shaped, which engage correspondingly inclined recesses 9, 9', on the roof and floor of the coupler head respectively. The projections 8, 8' and recesses 9, 9', are adapted to transmit a portion of the buffing 75 and pulling strains, and they also operate to prevent the forward end of the knuckle from bending outwardly away from the guard arm when subjected to pulling strains.

Under heavy pulling strains the knuckle 80 has a tendency to pull out of place, and with ordinary construction, if the knuckle does pull out of place its hub will travel away from the guard arm side and the proper gage between the nose of the knuckle 85 and the guard arm 10 will not be maintained. This condition, however, is obviated in my device, since, if the knuckle pulls forwardly, the forward walls of the recesses 9, 9', and the co-operating forward sides of 90 the projections 8, 8', being approximately parallel with the face of the guard arm 10, will prevent the increasing of the distance between the nose of the knuckle and the guard arm. The bosses w, w' on the coupler 95 ears 3 assist these bearings in preventing lateral movement of the knuckle.

Buffing bearings on the coupler head for the knuckle are provided in the raised bosses x, x' on the opposite inner surfaces of the 100 coupler ears 3, at y on the coupler side wall to the rear of the hub, at z, z' on the rear walls of the recesses 9, 9' through the rear walls of the projections 8, 8', and at w, w' on the rear side of the knuckle tail and the 105 side wall of the coupler head respectively. In the drawings the knuckle is shown in the position which it occupies under a pulling

strain, that is, there is clearance or backlash between the rear side w of the knuckle tail and the side wall w' of the coupler head. It will be understood, however, that under 5 buffing stresses this clearance will be taken up and the surfaces w and w' will come into buffing contact. There is no buffing contact, however, between the rear end of the knuckle tail and the coupler head, in any position of the knuckle.

10 The construction and operation of the other parts of the coupler which I prefer to use with the parts described above, are as follows:

15 The lock C has a flat face 12 for locking engagement with the front face 11 of the knuckle tail, and a vertical face 13 on the side opposite the face 12, for engagement with the coupler head.

20 14 is the leg of the lock, which coöperates with the opener D for locksetting and knuckle-throwing, and 15 is the locksetting shoulder thereon. On the forward side of the lock is a projection 16 which coöperates 25 with a shoulder 17 in the coupler head forward of the lock cavity, so that when the lock is lifted by the lifter E, which has a slotted connection with the rear side of the lock, the projection 16 will engage the shoulder 17 and the lock will fulcrum thereabout and its leg 14 will coöperate with the arm 18 of the knuckle thrower D, to swing the knuckle-thrower about its pivot 19, so that the arm 20 will throw open the knuckle.

30 The knuckle engaging end of the opener D has a curved surface which is designed to coöperate with a surface on the under side of the knuckle tail as shown in dotted lines in Fig. 1, in such a way that it will throw 35 the knuckle by means of a rolling action and with the minimum amount of sliding friction, that is, the opener is so pivoted with relation to the length of its knuckle-throwing end, that said end is caused to move in 40 substantially the same line as the line of movement of that portion of the knuckle tail with which it coöperates. This prevents any binding of the pulling surfaces 45 between the knuckle and the coupler head, 50 during the opening movement.

It is obvious that many changes may be made in the coupler which I have described

and shown herein, without departing from my invention, since—

What I claim is:

1. In a car coupler, a coupler head, a knuckle having a tail, inclined projections on the knuckle tail, bearings in the coupler head coöperating with said projections to force the nose of the knuckle as it moves forwardly under pulling stresses, toward the guard-arm side of the coupler, the corresponding faces of said projections and bearings being arranged tangentially to the bearing on the hub and substantially parallel to the guard arm face.

2. In a car coupler, a coupler head, a pivot pin and a knuckle having a tail, and bearings on the hub of the knuckle coöperating with ears on the coupler head, inclined bearing surfaces on the top and bottom of the knuckle, forming a continuation of the hub bearing against the ears and extending tangentially and rearwardly therefrom and transversely of the knuckle and toward the rear portion thereof, the said bearing surfaces on the knuckle being substantially parallel with the guard arm face to maintain the nose of the knuckle substantially at the same distance from the guard-arm under pulling stresses.

3. In a car coupler, a coupler head, a knuckle and a pivot pin therefor, ears on said coupler head to which said knuckle is pivoted, inwardly projecting bosses integral therewith and concentric with the pivot pin hole and of less diameter than said ears, coöperating shoulders on the hub of the knuckle, rearwardly inclined bearings forming continuations of said shoulders arranged tangentially thereto and substantially parallel to the guard arm face, and extending transversely of the knuckle tail on the upper and lower surfaces thereof, and corresponding bearings in the coupler head, said bearings comprising means for causing the nose of the knuckle to move toward the guard-arm side when the knuckle moves forwardly under pulling stress.

ARTHUR J. BAZELEY.
